UNITED STATES PATENT OFFICE

2,610,218

INDUCTION METAL MELTING FURNACE

Karl A. Lang, Glenview, Ill., assignor to Lindberg
Engineering Company, Chicago, Ill., a corpora-
tion of Illinois

Application April 29, 1950, Serial No. 159,647

2 Claims. (Cl. 13—29)

1

This invention relates to metal melting furnaces and more particularly to multiple chamber furnaces of the submerged channel type.

In furnaces of this type it is desirable to elevate the channels at one end so that they are more readily accessible for cleaning. Preferably the channels are arranged at an acute angle to the horizontal so that a cleaning tool can be inserted into their upper ends through one of the chambers to clean the channels without requiring that the furnace be emptied.

While this construction is desirable for cleaning, it presents one serious drawback which makes its use impractical in a furnace of conventional design. In ordinary operation of furnaces of the submerged channel type in which melting is produced by electrical windings around the channels, the metal flows in the channels and produces a relatively violent agitation in the chambers. When sloping channels are employed opening relatively close to the top of one of the chambers a severe surface agitation or boiling of the metal occurs in such chamber, causing excessive oxidation and resulting in an unsatisfactory melt.

According to the present invention, I have discovered that this undesirable agitation of the metal can be reduced or eliminated by providing the channels with specially shaped flared openings. Further limitation of agitation and other advantages can be obtained by forming the chamber into which the upper ends of the channels open with a sloping outer wall and a parallel vertically spaced inner wall defining a shoulder overhanging the channel openings. Thus it is possible in accordance with the present invention to provide an entirely practical and operative furnace in which the channels are readily accessible for cleaning and in which surface agitation of the metal is minimized and the provision of a furnace having these desirable features constitutes the principal object of the present invention.

Another specific object is to provide a furnace of the submerged channel type in which the channels are provided with openings flaring toward each other to minimize agitation of the molten metal.

Still another object is to provide a multiple chamber furnace in which one of the chambers has a sloping outer wall and a parallel inner wall defining a shoulder overhanging the channel openings. This construction assists in reducing agitation of the metal and facilitates loading the furnace without unduly increasing the exposed area of molten metal.

2

The above and other objects and advantages of the invention will be more readily apparent from the following description when read in connection with the accompanying drawing, in which:

Figure 1 is a horizontal section through a furnace embodying the invention on the broken line 1—1 of Figure 2;

Figure 2 is a vertical section on the line 2—2 of Figure 1; and

Figure 3 is a partial section on the line 3—3 of Figure 2 showing the channel openings in elevation.

The furnace as shown comprises a casing or housing 10 which may be of metal and which is lined with heat insulating material 11. The insulating material supports a furnace body 12 which may be built up of ceramic or like material. The body is formed with a melting chamber 13 and a holding chamber 14 spaced horizontally and connecting by a pair of sloping cylindrical tubes or channels 15 which open into the chamber 13 at a higher level than that at which they open into the chamber 14. A magnetic core 16 is arranged around the channels and is energized by alternating current windings, not shown, to induce a melting current in the metal in the channels in the usual manner for furnaces of this type.

With the furnace as so far described the electrical action causes a flow of metal in the tubes and produces agitation of the metal in the chambers near the tube openings. Since the tubes are relatively close to the surface of the metal in chamber 13, there is a tendency to cause a severe surface agitation or boiling effect in this chamber. At the same time it is desirable to arrange the channels with a relatively steep slope as shown so that a cleaning tool can be inserted easily through the chamber 13 to clean the tubes and to obtain a better melting action.

According to the present invention this surface agitation is reduced or eliminated by providing a specially flared shape at the channel openings. As shown, the channels 15 terminate at their upper ends in flared generally rectangular openings defined by top walls 17 substantially aligned with the tops of the channels and at most flaring only very slightly. The outer sides 18 of the openings which lie closely adjacent to the outer sides of the chamber 13 are substantially aligned with the outer sides of the channels. The openings have approximately horizontal bottoms 19 which lie at an acute angle to the tube axes and their inner or adjacent sides 21 flare sharply toward each other. Thus the

openings flare toward each other and are substantially straight continuations of the channels at their tops and outer sides.

Actual experience with furnaces having channel openings constructed as shown demonstrates clearly that the agitation in the chamber 13 is materially reduced to the point that the power input can be substantially increased without causing severe surface agitation or boiling. The exact reason for this is not clearly understood but it is believed to be due to the fact that flows from the tubes are directed toward each other and have a counteracting or cancelling effect on each other. In any event experiments with outlet openings of different shapes have shown that when either the tops or outer sides of the openings are flared or when the bottoms are flared below the horizontal or when the flare of the inner sides toward each other is omitted severe surface agitation is present resulting in unsatisfactory operation.

According to another feature of the invention, the melting chamber 13 is forming with a sloping outer wall 22 extending at an acute angle to the vertical. At its bottom the wall 22 joins a short vertical wall 23 in which the channel openings are formed and an inner wall 24 parallel to the wall 22 joins the vertical wall 23 just above the channel openings. The wall 24 forms a shoulder overhanging the openings and further tends to reduce surface agitation of the metal while also reducing the exposed surface.

The sloping wall 22 is very advantageous in adding metal ingots or the like. In adding metal, the cold metal pieces can be slid down the wall 22 and will enter the molten metal smoothly without splashing. Also the slope provides a large amount of space between the channel outlets and the outer wall of the chamber 13 for insertion of a cleaning tool into the channels and manipulation of the tool in claiming the tubes.

In relatively deep furnaces having a relatively wide holding chamber 14 the channel openings in the holding chamber are unimportant. However, in many furnaces the holding chamber is narrow or fairly shallow or both and agitation of the metal in the holding chamber may become severe. In these furnaces the openings in the holding chamber are preferably formed in the same way as those in the melting chamber with bottom surfaces 25 and outer side surfaces 25a parallel to the channels, horizontal top surfaces 26, and inner side surfaces 27 flaring toward each other like the surfaces 21. This construction eliminates or minimizes the agitation in the holding chamber.

While one embodiment of the invention had been shown and described in detail it will be understood that this is illustrative only and is not

to be taken as a definition of the scope of the invention, reference being had for this purpose to the appended claims.

What is claimed is:

- 5 1. A metal melting furnace comprising a pair of horizontally spaced chambers, a plurality of channels connecting the chambers and lying at an acute angle to the horizontal to open into the chambers at different levels, the upper ends of 10 the channels terminating in openings which are substantially flared in a horizontal plane toward each other and having their upper and outer edges lying in substantially straight lines continuous with the upper and outer boundaries respectively of the channels and electrical means mounted adjacent to the channels to induce a flow of electric current through the metal therein and in the chambers.
- 15 2. A metal melting furnace comprising a pair of horizontally spaced chambers, one of the chambers being defined by an outer wall lying at an acute angle to the vertical, a vertical wall joining the lower end of the outer wall, and an inner wall parallel to the outer wall and joining 20 the top of the vertical wall, and channels connecting the chambers and opening into said one of the chambers adjacent the top of the vertical wall, the channels sloping downward at an acute angle from said opening toward the other chamber, the inner wall defining a sloping shoulder overhanging the channel openings, and means defining outlets for the upper ends of the channels which are substantially flared in a horizontal plane toward each other and having their 25 top and outer side surfaces lying in substantially straight lines continuous with the upper and outer boundaries respectively of the channels and electrical means mounted adjacent to the channels to induce a flow of electric current 30 through the metal therein and in the chambers.
